ABSTRACT: A shadow mask is mounted within the faceplate panel of a cathode ray tube for color television at the top and at each side. One of the side mountings is a direct connection which is nonresilient in a horizontal direction and formed by a bracket fixed to the shadow mask frame and defining a socket for interlocking with the side mounting stud. In one embodiment, this direct connection prevents a lateral motion of the shadow mask frame relative to the faceplate panel while permitting removal of the shadow mask by movement axially of the frame. The top and other side connections are resilient connections, and they are designed to permit a predetermined hinging motion of the shadow mask as it heats up for rotating the mask about the direct connection toward the viewing area thereby correcting for misregistration of the shadow mask apertures with their associated phosphor dot pattern as the shadow mask expands. In one embodiment, the mounting system both rotates and translates the mask toward the screen for correcting for misregistration.

**SHADOW MASK MOUNTING SYSTEM FOR COLOR
KINESCOPE INCLUDING ONE SIDE DIRECT
CONNECTION**

BACKGROUND

The present invention relates to a color television kinescope of the kind which employs a shadow mask; more particularly, it relates to a three-point suspension system for mounting the shadow mask within the peripheral flange of the faceplate panel.

In shadow mask cathode ray tubes of the kind with which the present invention is concerned, three electron beams are deflected across the viewing area or screen in a raster. Three separate sets of phosphor dots are deposited on the screen and each set of dots produces an image of a different primary color when excited by its associated electron beam. Each of the electron beams is modulated by a video signal representative of one of the three color components. The three resulting images are so closely spaced that they appear as one on the screen. Desired colors in the image are produced by excitation of the different phosphors at each incremental area of the reproduced image.

An apertured shadow mask is placed adjacent the phosphor pattern on the screen for selective excitation of the dots. The mask has the order of 300,000 apertures. Each of the apertures is associated with one set of three (i.e. one of each color-producing phosphor), or triad of the phosphor dots, and the beams are so focused that the angle by which each beam passed through the mask aperture causes the beams to cross while passing through the aperture and separate whereby each beam impinges only on its associated phosphor dot to the exclusion of the adjacent dots. It is obvious that extreme precision is required in the construction of the tube and in the mounting of the shadow mask within the tube so that the electron beams do not impinge on dots associated with different color since this would generate incorrect color.

During operation, the mask has a greater expansion than the faceplate panel; hence, there must be some allowance for this expansion in the mounting system. By using a resilient or spring mounting system, this problem can be overcome.

Normally, the dots are deposited in three separate operations before the funnel portion of the tube is bonded to the faceplate panel. After each exposure of the panel to actinic light, the shadow mask must be removed for a washing.

Since the shadow mask is repeatedly inserted and removed in the faceplate panel of the cathode ray tube during the manufacturing process, not only must the connections between the shadow mask and the faceplate panel be such that the shadow mask may be easily removed, but it is highly desirous that these connections be almost inflexible so that proper alignment of apertures with their triads may be repeatedly achieved. This, however, does not solve the unequal expansion problem. Normally the faceplate panel is arranged in a horizontal position during the deposition of the phosphor dots, whereas during normal operation it is arranged in a vertical or standing position. Hence, any sag of the faceplate panel under its own weight will either in the horizontal or the vertical position will produce errors in the ultimate image.

Another more critical problem in locating the mask is that of residual deformation of the springs when they are subjected to high temperature during tube processing.

In the past, all of these requirements have militated against a common solution. Prevailing commercial mounting system use either a three-connection or a four-connection system. Some of these systems interpose flat steel springs between the shadow mask frame and the peripheral flange on the faceplate panel. Such mountings have not totally eliminated the problem of sag; and even the employment of heavier material for the steel springs have not completely overcome the problem of residual deformation.

Although it provides a more rigid mounting, the four-point suspension system requires a custom welding of at least one

spring connection. The three-point system, while avoiding the need for custom welding, is less stable. It will be appreciated that usually in the three-point system, there is a top connection which is centered and two side connections which are located below the horizontal center of the mask.

Thus in the three-point system, any change in the applied force of either of the side springs will produce a bending moment in the mask tending to rotate it about the axis of the tube since there is only a second-order retaining effect in this type of system, as distinguished from the four-point system.

Aside from the fact that a permanent connection between the shadow mask and the faceplate panel is not feasible because of the removal requirement, it is also known that the shadow mask becomes heated during operation as the scanning electron beams impinge on the shadow mask. The temperature of the shadow mask during normal operation will rise to 20—30°C. above that of the faceplate panel; and during processing the rise will be 430°C. At the high processing temperature, the change in force in the side springs produces a coupling moment in the screen to cause a slight rotation and thus a misregistration when in normal operation.

SUMMARY

The present invention employs one direct, nonresilient side connection between the shadow mask frame and the faceplate panel at the side of the shadow mask. As used herein, the phrase "direct connection" means that there is no intervening mounting spring so that once the connector is seated on the stud, the mask cannot be urged closer to the stud. This direct connection takes the form of a collar or socket fixed to the shadow mask frame and defining an aperture for receiving the mounting stud on the side of the faceplate flange.

The other side connection is spring connection using a flat steel spring which facilitates removal of the shadow mask from the faceplate panel and allows expansion; and this connection preferable employs means for displacing the shadow mask relative to the screen when heated by hinging it about the direct connection. This compensates for the partly linear, partly radial expansion of the mask due to heating.

The top connection between the flange and the shadow mask frame is similar to the side connection except that the allowed motion is somewhat less to correlate with the hinging action of the side connection except that the allowed motion is somewhat less to correlate with the hinging action of the side connection.

With this improved mounting, it has been found that the suspension of the shadow mask within the faceplate panel is at least as rigid as if a four-point connection were employed. Further, compensation for misregistration is accomplished, while allowing easy removal of the shadow mask from the faceplate panel.

Other features and advantages of the instant invention will be obvious to persons skilled in the art from the following detailed description of preferred embodiments accompanied by the attached drawing; wherein identical reference numerals will refer to like parts in the various views.

THE DRAWING

FIG. 1 is a rear elevation of a shadow mask mounted within a faceplate panel;

FIG. 2 is a side view of a conventional mounting using a flat steel spring;

FIG. 3 is a closeup view of the direct side connection between the faceplate panel and the shadow mask frame;

FIG. 4 illustrates the hinging motion of the shadow mask about the direct side connection as the shadow mask expands due to heating; and

FIGS. 5—6 illustrate an alternate embodiment of the direct side connection.

DETAILED DESCRIPTION

Referring then to the drawing, and particularly to FIGS. 1 and 2, a faceplate panel is generally designated 10; and it includes a curved viewing area 11 and an integral, peripheral flange 12 which extends toward the rear or constricted neck portion of the tube (not shown) for attachment to the funnel of the tube.

The phosphor dot pattern is deposited on the inside of the curved portion 11 as at 13 (FIG. 2). This defines the screen or viewing area.

Adjacent the screen is an apertured shadow mask 15 which generally conforms to the concave contour of the front panel 11. A heavier, rigid frame 16 is attached about the periphery of the shadow mask 15 for mounting to the faceplate panel 10.

In the illustrated embodiment, there are three connections between the shadow mask frame 16 and the peripheral flange 12 of the faceplate panel 10; and these include a first side connection generally designated 17, a second side connection generally designated 18, and a top connection 19. At each of these connections 17-19, a mounting stud is embedded in the flange 12. These studs are designated respectively 20, 21, and 22.

In FIG. 2, the connector 18 is seen in more detail as comprising first and second arched arms 25 and 26 welded at top and bottom to the frame 16. The arms 25 and 26 are curved toward the viewing area or front of the tube. A crossbar 27 is fastened between the center portions of the arms 25 and 26, and a tab 28 in the form of a flat steel spring is connected to the crossbar 27. The spring 28 has an aperture 29 for fitting over the side stud 21.

More detail on the side fitting 18 as well as the top connection 19 can be obtained from the copending, coowned application of Schwartz and Javorik for COLOR TELEVISION TUBE MASK MOUNTING, U.S. Pat No. 3,999,319, issued Aug. 27, 1968. It will be noted that as the shadow mask frame heats up, the arms 25 and 26 (composed of metal having a coefficient of thermal expansion less than that of the metal frame 16) will straighten out as the shadow mask is heated, thereby translating the edge of frame 16 toward the screen. Alternatively, bimetal mounting means may be used at the connections 18 and 19 for shifting the mask as its temperature rises.

The connection 19 which couples the top of the shadow mask to the flange 12 is similar to the side connection 18 but is slightly modified to allow approximately one-half of the total movement as that of the side connection 18, for reasons explained below.

Referring now to FIG. 3, the direct side connection 17 is shown in more detail. As can be seen therein, the conventional mounting stud 20 projects inward of the flange of the faceplate panel, and it defines a slight taper or conical sidewall 32 which is truncated. Welded to the outer side of the frame 16 of the shadow mask is a base or mounting plate 33 to which is fastened a U-shaped channel member 34 having a aperture or socket 35 for receiving the stud 20. It will be appreciated that the socket 35 interlocks with the mounting stud 20 to prevent a radial or lateral motion of the cap 34 relative to the mounting stud 20. At the same time, however, the shadow mask may be easily removed from this interlocked connection by depressing the mounting springs at the connections 18 and 19, and with a slight lateral motion combined with a little turning, the shadow mask is simply and easily removed from the faceplate panel. It will be appreciated that with this direct connection at 17, incremental variances in the force applied by the spring at 18 will not affect the mask since there is no play or resiliency transversely of the axis of the tube at the direct connection.

In addition to the facility of removing the shadow mask from the faceplate panel, the direct connection 17 allows a slight rotation or hinging of the shadow mask relative to the screen 13. As illustrated most clearly in FIG. 4 by the dotted line designated 15', as the shadow mask is expanded both radi-

ally and linearly due to the impinging electron beams, the shadow mask 15 will rotate toward the screen 13 for correcting misregistration. This is illustrated in the drawing by reference to the single aperture 36 (exaggerated for purposes of illustration) in the shadow mask 15 which, if the hinging effect were not available would move laterally to the right; and in this case it is hinged or rotated slightly forward and takes the position 36' which compensates for misregistration.

With this inventive mounting of the mask, it has been observed that the shift of the mask under its own weight is approximately 0.001 in., whereas with an older type of flat steel spring the sag was close to 0.005 in., and even with a more rigid and heavy spring, the sag was up to 0.002 in., which is an appreciable amount of relative movement considering the diameter of the apertures, it being greater than 10 percent of the diameter.

As an example for the specific case for a 25 inch tube, the cycle lengths for bimetal compensation are as follows: at the connection 19, the cycle length is 0.350 in., for the connection at 18, the cycle length is 0.473 in.

Referring now to FIGS. 5-6, there is illustrated an alternate form for the direct side connection 17 which accomplished both the hinging action heretofore mentioned and, in addition, translates the side of the frame which receives the direct connection toward the screen. The previously described suspension system wherein there was compensation only at the center of the mask and at the far end of the mask, provided compensation only along the major axis of the tube; and it does not compensate against the expansion along the minor axis. Better compensation may be accomplished by the arrangement illustrated in FIGS. 5-6 which adds compensation at the direct side connection.

As seen most clearly in FIG. 6, which is a side view of the direct connector, first and second parallel bimetal strips 50 and 51 are coupled together in spaced relation by means of first and second U-shaped spacers 52 and 53, the bases of which are welded to the side of the frame 16. The bimetal strips 50 and 51 normally extend in a vertical direction, and each consists of three separate sections, designated respectively as 50a, 50b, 50c, and 51a, 51b, and 51c. A third U-shaped spacer 55 is fixed between the strips 50 and 51 with its base extending above them. The spacer 55 has an aperture 56 which receives the stud 20'. This structure forms a socket for the direct connection.

The composition and structure of each of these strips is more fully disclosed in the copending, coowned application of Schwartz and Javorik for SUSPENSION SYSTEM FOR COLOR TELEVISION TUBE MASK, U.S. Pat. No. 3,449,611, issued Jun. 10, 1969.

Each of the sections comprising the strips 50 and 51 is composed of a bimetal pair having different coefficients of thermal expansion. In the illustration, the metal having the larger coefficient of expansion is shown as having a greater thickness; and the center sections 50b and 51b are in reversed position relative to their end sections.

Thus, the bimetal strips 50 and 51 are designed to assume the curved shapes respectively designated 50' and 51' for moving the socket 55 rearward of the fixed mounting 52 and 53. Since the stud 20' is received in the aperture 56, this effect moves the shadow mask forward toward the screen.

By providing for a temperature-sensitive connection at both side connections and at the top connection, compensation for misregistration is made along both the major and the minor axes of the tube. For this particular arrangement, and for a 25-inch television tube, the cycle length of the bimetal at the mounting location 17 is 0.175 in., the cycle length at mounting location 19 is 0.315 in., and the cycle length has been calculated to give a movement that effects compensation at the half-length of the minor axis thereby cutting the misregistration at the end in half and distributing the error evenly between the end point and the center point.

With these arrangements it can be seen that for any changes in the force of the spring 28 at the right side of the tube (as

viewed in FIG. 1) there will be no corresponding moment coupled to the mask even though the spring may be heated substantially as during processing.

Having thus described in detail preferred embodiments of the invention, it will be obvious to persons skilled in the art that certain structural elements may be modified or replaced by equivalent components; and it is therefore intended that all such substitutions and modifications be covered as they are embraced within the spirit and scope of the appended claims.

We Claim:

1. In a color television tube including a faceplate panel defining a viewing screen and a peripheral flange depending from said screen and having only a top and first and second side mounting studs extending radially of said tube, and further including shadow mask means, a three-point mounting system incorporated into said mask means comprising: a mask defining apertures in register with the phosphor dot pattern on said screen; a frame secured to the periphery of said mask; means defining a socket radially fixed to one side of said frame for receiving and interlocking with said first side stud of said flange, said socket means and said stud cooperating to form a direct connection thereby preventing relative lateral movement between said frame and said flange while permitting said

frame to be removed by motion radial of said tube; first resilient means mounted on the top of said frame for resiliently coupling to said top mounting stud on said flange; and second resilient means on the other side of said frame for resiliently coupling to said second stud of said flange.

2. The structure of claim 1 further comprising means associated with said second resilient coupling means and said top resilient coupling means for rotating said mask bodily toward said viewing area in response to temperature increase about said direct connection.

3. The structure of claim 1 wherein said side resilient mounting means includes flat steel spring means permitting movement of said mask relative to said screen as the temperature of said mask rises, and means associated with said top resilient mounting means permitting movement of the top of said frame relative to said screen, the movement of said side being greater than that at said top.

4. The structure of claim 2 further comprising temperature-sensitive means associated with said socket means for moving said frame toward said screen in response to a predetermined temperature rise whereby said mask is both rotated and translated toward said screen in correcting for misregistration.
